UNITED STATES PATENT OFFICE.

LOUIS ROTELLA, OF MONTREAL, QUEBEC, CANADA.

SPARK PLUG.

Application filed June 10, 1925. Serial No. 36,246.

The invention relates to a spark plug, as described in the present specification and illustrated in the accompanying drawings that form part of the same.

- 5 The invention consists essentially of the novel features of construction pointed out in the claim for novelty following a description containing an explanation in detail of an acceptable form of the invention.
- 10 The objects of the invention are to intensify the electric spark in ignition systems; to eliminate the troubles incident to the failure of the spark due to accumulations of oil and grease and resulting carbon; to 15 lengthen the life of the plug and thereby save money to the consumer; to minimize the attention required to maintain the sparking points in good condition; to visualize the condition of the electric connections for producing the spark and determine the state of 20 individual plugs; to reduce the cost of manufacture of sight plugs, and bring them within the range of standard plugs; to minimize the effect of heat generation within the plug; 25 and generally to provide an efficient, economical and reliable spark plug.

In the drawings, Figure 1 is an elevational view of the preferable form of the plug complete.

- 30 Figure 2 is a vertical sectional view of the plug illustrated in Figure 1.

Figure 3 is a cross sectional view on the line 3—3 in Figure 1.

- Figure 4 is an elevational view of a slight 35 modification of the form illustrated in Figure 1.

Figure 5 is a vertical sectional view of the modified form shown in Figure 4.

- Figure 6 is an elevational view of another 40 modification of the plug showing a metal cap holding a transparent cover for sight apertures.

Figure 7 is a vertical sectional view of the form shown in Figure 6.

- 45 Figure 8 is a vertical sectional view of a slight modification of the form illustrated in Figures 6 and 7.

- Figure 9 is a detail of the porcelain body of the forms shown in Figures 6, 7 50 and 8.

Figure 10 is a cross sectional view on the line 10—10 in Figure 6.

Figure 11 is a cross sectional view on the line 11—11 in Figure 6.

- 55 Figure 12 is an elevational view of another

form of the plug having the cap screwed to the porcelain body on to a reduced upper end.

Figure 13 is a vertical sectional view of the form illustrated in Figure 12.

Figure 14 is a detail of the porcelain body in the form illustrated in Figures 12 and 13.

Like numerals of reference indicate corresponding parts in the various figures.

Referring to the drawings, in Figures 1, 2 and 3 the preferable form of the plug is illustrated and in these figures the shell *a* and nut *b* are of a conventional form and contain the porcelain body *c* having a tapered lower portion *d* and tapered upper portion *e* extending to an enlarged waist portion forming upper and lower shoulders for the gaskets *g* and *h*. The conducting rod *i* projects above and below the body *c* and at the lower ends coacts with the ground connection *j* from the shell in producing the spark for ignition purposes.

The gasket *h* is between the shell and the porcelain body while the nut *b* screws down on the gasket *g* which is well known construction.

The tapered upper end *e* of the porcelain body allows ample space between itself and the nut *b* for the purposes of this construction and the translucent hollow cap *k* occupies a part of this space being inserted in the nut *b* and so closely fitting therewith as to constitute therewith a unit in the finished plug.

The cap *k* has an orifice *l* at the upper end and this orifice is threaded and a bushing *m* introduced in the opaline, amber or other translucent material centrally at the top and forming a part therewith.

The conducting rod *n* is threaded and screws into the orifice *l* to form the gap *o* within the hollow gap for intensifying the spark at the ignition gap and furnishing a sight spark, which will illuminate the complete upper portion of the plug. The rod *n* is adjusted to its position by the knurled nut *p* and locked by the customary thumb nut *a*, from which the connection is made to the coils.

It will be seen that the complete cap and nut may be removed from the shell together thereby disclosing the porcelain body and lower conducting rod, thus taking apart the plug in a moment for cleaning purposes.

In Figures 4, and 5, the only difference

from the form shown in Figures 1 and 2 is the cylindrical form of the upper reduced end *r* of the body *s* and the mounting of the translucent hollow cap *t* on said cylindrical end *r* as well as turning the upper end *u* of the shell *v* over the gasket *w* on the shoulder *y* otherwise the plug is precisely the same.

In Figures 6, 7, 8, 9, 10 and 11, the numeral 10 indicates the body of the plug which is preferably made of porcelain as customary in spark plugs, though the construction of the porcelain body in this invention is different to meet the requirements.

15 The body 10 is formed with the reduced upper end portion 11 moulded in cylindrical shape and extending upwardly from the annular shoulder 12, said reduced portion having a bronze threaded bushing 13 centrally 20 embedded therein and having a threaded orifice 14 forming a rod entrance to the interior of the sight sparking chamber 15, which is within the reduced upper portion 11, the wall of this chamber having the windows or apertures 16 as sight openings thereinto.

The threaded conducting rod 20 is formed at its upper end with the driving slot 21 and at its lower end with the point 22, coacting with 30 the point 18 within the chamber 15 in creating the sight spark across the gap 23 between the two points.

The rod 20 is screwed into the bushing 13 and therethrough into the chamber 15 to 35 form the said gap 23 and at its upper end extends through the cap 24. The cap 24 is of brass or other non-rusting metal and is formed of the disk top 25 having the central rod hole 26 and the peripheral downwardly 40 extending flange 27.

The cap 24 rests on the upper end of the porcelain body 10 and caps the tubular glass covering 28 glazing the sight windows 16. The flange 27 fits snugly over the glass tube 28 and centers the latter as the rod 20 maintains the cap in a central position, the annular under side of the disk top 25 engages the said glass and brings it into contact with the shoulder 12 and flush with the periphery of 45 the middle portion of the body 10. The glass covering 28 for the sight end of the body 10 is purposely spaced all around from the periphery of the reduced portion 11 thereby providing an air space that will eliminate 50 the accumulation and ignition, or explosive and inflammable gases incident to the situation of the sight sparking chamber 15.

The adjusting nut 29 having the knurled edge face 30 is screwed tightly to the cap 24 on the rod 20 and the thumb nut 31 is 55 screwed on said rod 20 against the nut 29 and holds the wire connector.

The annular flange 32 from the body 10 and the tapering base portion therebelow are 60 contained within the metal shell 33 and the

ground connection 34 projects from the shell, and coacts with the point 19 in creating the spark for ignition purposes.

The shell 33 is externally threaded at 35 as customary in spark plugs, for the connection with the engine, and internally threaded at 36 to receive the securing nut 37, which encircles the middle portion 38 of the body 10, thereby securely holding the porcelain in place and completing the plug.

In regard to the escape of gases from the engine the gasket 39 is introduced between the porcelain and the shell and the gasket 40 is introduced between the shell locking nut 41 and the shell, therefore no gases can escape through the plug.

In Figure 8 a modification of the plug is shown, still having feature already described, namely the space between the glass and the sight chamber wall, but in this form of the invention the sight chamber wall 41 is a separate piece made of a suitable insulating material with the apertures 42 looking into the sight chamber 43 and the under nut recess 44. The chamber wall 41 rests on the body 45, which is of greater diameter than the outside measurements of the sight chamber, thereby forming the shoulder 46, on which the tubular glass 47 stands, said glass being flush with the outer edge of the shoulder to leave a space 48 between the outer surface of the wall 41 and the inner surface of the glass 47 for the circulation of the air to avoid the accumulation of inflammable gases.

The conducting rod 49 is introduced in the body 45 and may be permanent therewith or it may be held by the nut 50 in the recess 44 as found more desirable.

The rod 51 screws into and through the upper portion of the sight chamber wall 41 and is locked by the nut 52 and thumb nut 53 screwed against the cap 54 flanged at the outer edge 55 to receive the glass 47 and pierced centrally for the rod 51, the latter centering said rod to hold the glass steady and in its spaced position from the sight chamber wall.

The rods 49 and 51 form the sparking gap 56 in the sight chamber 43 and the rod 49 and ground wire 57 form the usual sparking gap for ignition purposes.

The body 45 is formed with a flange 58 midway of its length and a tapered lower portion 59 fitting with said flange in the shell 60, the latter being turned over said flange 58 and a holding flange 61. The gasket 62 is introduced between the flanges 58 and 61 and the gasket 63 is introduced between the flanges 58 and the conveying surface 64 of the shell 60.

In Figures 12, 13, and 14 a very efficient form of this invention is shown, wherein the transparent dome 65 of opaline or other translucent material takes the place of the

upper end of the usual porcelain body and has the metal bushing 66 placed therein in the moulding formed of a central threaded rod hole through the top, the inner wall 5 for a short distance inwardly having the thread 67.

The porcelain body 68 is formed with a middle flange 69 and tapering lower portion and above the flange 69, the cylindrical portion 70 which is reduced to form the threaded nipple 71 screwing into the thread 67 of the dome 65.

The dome 65 screws on to the nipple 71 abuts and engages the fibre washer 72 15 rounding said nipple thereby insuring a tight hold for the dome on the porcelain.

The conducting rod 73 is placed centrally in the porcelain body 68 at the moulding and therefore remains permanently there- 20 with and this rod 73 projects upwardly into the dome 65 and terminates in the point 74 in the sight chamber 75 and enclosed by said dome. The upper end of the rod 73 projects below the porcelain body and terminates in 25 the sparking extremity 76, which with the ground connector 77 from the shell 78 forms the usual sparking gap 79.

The connector rod 80 is threaded and screws into and through the bushing 66 and 30 is adjusted with respect to the point 74 to form the sparking gap 81 which is within the sight chamber.

The knurled nuts 82 and 83 are mounted on the rod 80 and screw tightly to the bush- 35 ings 66 and are adapted to hold the connector to the wiring.

The shell 78 is formed with the wrench flats 84 and the reduced screw threaded portion 85 for attaching the plug to the engine 40 head and at its upper end 86 it is turned over the flange 69 of the body 68, the washer 87 and 88 being introduced between the shell and the body flange thus firmly holding the body in place.

45 This form of the plug is to be specially commended as the whole top of the plug is illuminated and it is not necessary to watch

for a flash as the semi-translucent top lights up and shows very plainly without close investigation whether or not the ignition is in 50 good condition.

In the operation of this spark plug, the ground connection is made by screwing the shell into the cylinder head and the other connections are made to the upper conduct- 55 ing rod, as explained thus the current will flow along the two rods and in doing so will jump the sight gap making a slight spark and continuing will jump the usual gap between the ground connection and the lower 60 point. This construction considerably intensifies the spark due to the jumping of the sight cap and insures efficient and visible operation under most conditions.

The upper conducting rod is adjustable as 65 explained consequently by loosening the adjusting nut after loosening the thumb nut the threaded conducting rod can be delicately adjusted by a screw driver to fix the distance of the gap to a nicety.

70 It may be found desirable to mould the upper conductor rod with the top and permanently determine the sight gap, especially is this applicable in the opaline dome top type, which will of course eliminate the central bushing.

75 What I claim is:—

In a spark plug, a dome of translucent material having a circular bore through the upper wall thereof and a metal filler fixedly 80 secured in said bore and having a central threaded orifice therethrough, a threaded sleeve frictionally secured on the lower portion of said dome and extending therefrom and externally threaded, a shell formed to 85 receive said dome and forming a ground connection, insulating material therein, a lower conductor extending through said insulation into said dome, and a terminal having a conductor rod extending through said 90 metal filler into said dome.

Signed at Montreal, Canada, this 28th day of May, 1925.

LOUIS ROTELLA.
